UNITED STATES PATENT OFFICE.

JAMES BRYANT THOMAS, OF ST. LOUIS, MISSOURI.

DRAFT MECHANISM FOR RAILWAY-CARS.

SPECIFICATION forming part of Letters Patent No. 594,579, dated November 30, 1897.

Application filed February 8, 1897. Serial No. 622,543. (No model.)

To all whom it may concern:

Be it known that I, JAMES BRYANT THOMAS, a citizen of the United States, residing at St. Louis, in the State of Missouri, have invented 5 a new and useful Draft Mechanism for Railway-Cars, of which the following is a specification.

The invention relates to improvements in draft mechanism for railway-cars.

10 The object of the present invention is to improve the construction of draft mechanism for railway-cars and to prevent the frames of cars and the draft-timbers from being strained and otherwise injured through the lateral vibration of the draw-head and the draw-bar incident to the passage of a train over rough road-beds and around curves.

15 A further object of the invention is to provide a draft mechanism which will permit a draw-head and its draw-bar to vibrate laterally and thereby relieve the draft-timbers and the car-frame entirely of the strain resulting from such lateral thrusts when a rigid connection, such as the ordinary draft-timbers, is employed.

20 Another object of the invention is to facilitate a ready removal of the spring and the follower-plates in the event of the breakage of any of the parts and to enable new parts 30 to be readily supplied and assembled without necessitating the removal of the entire draft-rigging.

25 The invention consists in the construction and novel combination and arrangement of parts, as hereinafter fully described, illustrated in the drawings, and pointed out in the claims hereto appended.

30 In the accompanying drawings, Figure 1 is a perspective view of a portion of a car provided with draft mechanism constructed in accordance with this invention. Fig. 2 is a reverse plan view. Fig. 3 is a longitudinal sectional view. Fig. 4 is a similar view showing one of the draft-irons. Fig. 5 is a trans- 45 verse sectional view illustrating the manner of introducing a follower-plate into and removing it from the draft-irons. Fig. 6 is a detail perspective view of one of the draft-irons. Fig. 7 is a transverse sectional view 50 illustrating the construction of the supporting-stirrup of the draw-bar. Fig. 8 is a de-

tail perspective view of the bottom piece of the supporting-stirrup.

Like numerals of reference designate corresponding parts in the several figures of the 55 drawings.

11 designate a pair of similar longitudinal draft-irons arranged parallel with each other and designed to dispense with the ordinary draft-timbers usually arranged at each side 60 of the shank or draw-bar of a draw-head, and each draft-iron consists of a central rectangular frame or portion 2 and forwardly and rearwardly extending arms 3 and 4. The central rectangular frame or portion 2 receives 65 and forms ways for follower-blocks 5, which are held against lateral movement by upper and lower flanges 6 and vertical side flanges 7, located at the outer face of the draft-iron and extending around the rectangular opening of the frame or portion 2. The forwardly or outwardly extending arm 3, which is formed integral with the central portion of the draft-iron, extends from the top of the frame or portion 2 to the front or end transverse sill 8 70 and is arranged against a longitudinal draft beam or timber 9. The body portion of the upper arm 3 has its lower face flush with the lower face of the end sill 8 of the car 10 and is arranged above the plane of the shank or 75 draw-bar 11 of a draw-head 12, so that the latter and its shank or draw-bar are unconstrained at the sides to permit the draw-head to vibrate laterally without communicating any 80 of the strain to the draft-timbers or the frame 85 of the car.

85 The central frame or portion 2 is provided at its top with an upwardly-extending lug 13, which is arranged in a recess of the draft-timber 9 and serves to strengthen the construction. The inwardly or rearwardly disposed arm 4 extends from the bottom of the central portion or frame 2 of the draft-iron, making the construction perfectly solid and capable of withstanding successfully all 90 the strains incident to such draft mechanism. 95 The draft-iron is further strengthened by a longitudinal flange 16, extending from the 100

front end of the upper arm 3 to the rear end of the lower arm and provided with a vertical portion 17, which extends along the outside of the central portion or frame 2. As 5 clearly illustrated in Fig. 2 of the accompanying drawings, the draft-irons are sufficiently wide to permit the necessary lateral play or vibration of the car-coupling without any liability of the same coming in contact with the 10 strengthening-flanges 16, which are located at the outer faces of the draft-irons.

The follower-blocks 5, which are arranged at the ends of a spring 18 in the usual manner, are adapted to be readily removed from 15 the draft-irons without detaching the latter, and the draw-head and the other draft-rigging and the upper and lower flanges 6 are provided with central recesses or notches 19, forming entrances to the ways and enabling 20 the follower plates or blocks to be readily inserted in and removed therefrom, as illustrated in Fig. 5 of the accompanying drawings. The spring 18 is disposed on a draft-bolt 20, which is connected to the shank or 25 draw-bar in the usual manner by a pin, and its rear end is provided with a nut.

One of the bolts 16^a of each of the draft-irons is located directly opposite the entrance-recesses 19 and is adapted to prevent any 30 liability of the follower blocks or plates accidentally slipping through the entrance-recesses. These bolts, which are located opposite the entrance openings or recesses 19, are removed when it is desired to remove the following plates.

The draw-head and its shank or draw-bar are supported by a stirrup 21, depending from the end sill 8 and composed of vertical sides 22 and a bottom connecting-piece 23. 40 The sides, which pass through openings 24 of the end sill 8, are pivoted at their upper ends by bolts 25, disposed longitudinally of the car and arranged in perforations of knees or L-plates 26, the end sill being reinforced 45 at its upper face around the openings 24 by a suitable plate. The bottom piece 23, upon which the shank or draw-bar rests, has its ends 27 curved and bifurcated to receive the lower terminals of the sides 22, and the curved 50 ends 27, which are slightly hook-shaped, engage horizontal bolts or pins 28, which form pintles and hinge the lower ends of the sides 22 to the bottom cross-piece 23; but other forms of hinge-joints may be employed.

55 The openings 24 are tapering and gradually increase in width from the top of the sill 8 to the bottom thereof, in order to permit the stirrup to swing transversely of the car, to yield to all of the lateral vibrations and 60 thrusts of the car-coupling, and prevent the strain which usually results from such movements of the draw-head from being communicated to the car or the draft-timbers. By permitting the car-coupling to swing laterally instead of employing a rigid connection the framework of the car, the draft-timbers, and the draft-irons are absolutely relieved of

all the lateral strain which usually results when the draw-head and its shank or draw-bar are rigidly mounted between two draft-timbers in the ordinary manner and when a train is passing over rough road-beds or around curves. The openings 24 are also of sufficient longitudinal width to allow the stirrup a limited swing longitudinally of the car, 75 in order to permit the same to yield to any longitudinal thrust of the car-coupling.

It will be seen that the draft mechanism is simple and exceedingly inexpensive in construction, that it possesses great strength and 80 durability and increases the strength and stability of cars, and that it mounts the car-coupling in such a manner as to permit it to yield to all lateral thrusts and vibrations incident to the passage of a train over rough 85 road-beds and around curves and thereby relieves the framework of the car and the supporting devices entirely from such strain. It will also be apparent that it affords free access to the spring and the follower plates or blocks 90 and permits those parts to be readily assembled and removed without necessitating the removal of the other draft mechanism.

Changes in the form, proportion, and minor details of construction may be resorted to 95 without departing from the spirit or sacrificing any of the advantages of this invention.

What I claim is—

1. The combination with a car, and a draw-head, of a laterally-swinging stirrup supporting the shank or draw-bar of the draw-head and composed of vertical sides pivoted at their upper ends to the car, and a transverse bottom piece extending beneath the shank or draw-bar of the draw-head and hinged at its 100 ends to the lower terminals of the sides, substantially as described.

2. The combination with a car provided in its end sills with tapering openings, a draw-head, and pivots located at the upper ends of the tapering openings, of a jointed supporting-stirrup suspended from the said pivots and receiving the shank or draw-bar of the draw-head, the sides of the stirrup being arranged in the tapering openings, and the latter being of sufficient width to permit the stirrup to swing both transversely and longitudinally of the car, substantially as described.

3. The combination with a car, and a draw-head, of a stirrup depending from the car, receiving the shank or draw-bar of the draw-head and composed of sides pivoted at their upper terminals and provided at their lower ends with pins, and the horizontal bottom piece having its ends bifurcated to receive 125 the sides and curved to engage the pins, substantially as and for the purpose described.

4. The combination with a car, of the longitudinal draft-irons arranged in pairs, provided with ways and having upper horizontal 130 arms extending forward or outward, a draw-head having its shank or draw-bar located beneath the horizontal arms of the draft-irons, a draft-bolt connected with the shank

or draw-bar, a spring disposed on the draft-bolt, and follower plates or blocks receiving the draft-bolt and arranged in the ways of the draft-irons, substantially as described.

5. The combination with a car, of longitudinal draft-irons composed of rectangular frames forming ways, and flanges arranged at the outer faces of the frames and provided with entrance-recesses, follower-plates arranged in the ways of the draft-irons and adapted to be passed through the entrance openings or recesses of the flanges, a draw-head, a draft-bolt connected with the shank or draw-bar of the draw-head and with the follower-plates, and a spring disposed on the draft-bolt between the follower-plates, substantially as described.

6. The combination with a car, of longitudinal draft-irons comprising central rectangular frames forming ways, and upper and lower horizontal arms extending forward and rearward from the top and bottom of the frame, follower-plates detachably arranged in said ways, and a draw-head connected with the follower-plates, substantially as described.

7. The combination with a car, of longitudinal draft-irons comprising central rectangular frames forming ways and provided at their outer faces with flanges having entrance-recesses, and upper and lower arms extending

horizontally from the top and bottom of the frames, follower-plates arranged in said ways and adapted to be passed through the entrance-recesses, and bolts passing through the frames opposite the recesses, substantially as described.

8. In a device of the class described, a draft-iron composed of a central rectangular frame or portion forming a way and provided with entrance recesses or openings communicating with the ways and upper and lower arms extending horizontally from the top and bottom of the frame, substantially as described.

9. In a device of the class described, a draft-iron comprising a central rectangular frame forming ways, arms extending horizontally from the top and bottom of the frame, flanges extending around the rectangular frame and provided with recesses forming entrances to the said ways, the longitudinal strengthening-flange extending the entire length of the draft-iron, and the lug extending upward from the top of the same, substantially as described.

In testimony that I claim the foregoing as my own I have hereto affixed my signature in the presence of two witnesses.

JAMES BRYANT THOMAS.
